(57) **CLAIM**

The ornamental design for a relay connector, as shown and described.

DESCRIPTION

FIG. 1 is a front elevation view of a relay connector showing our new design;

FIG. 2 is a back elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front-top-left side perspective view thereof;

FIG. 8 is a front-bottom-left side perspective view thereof;

FIG. 9 is a back-top-right side perspective view thereof;

FIG. 10 is a back-bottom right side perspective view thereof; and,

FIG. 11 is a front-top-right side perspective view thereof in use condition.

The broken line in the figure drawing is included for the purpose of illustrating environment and forms no part of the claimed design.
